CLOTHES HANGER

Fred Stein, Long Beach, N. Y.

Application October 24, 1947, Serial No. 781,892

4 Claims. (Cl. 211—100)

1

The present invention relates to a clothes hanger, particularly of the type adapted to be horizontally extended for the engagement or disengagement of a plurality of coat hangers, and then to be folded into substantially upright position so as to support the garments in a relatively compact space within a clothes closet or the like.

An object of the invention is to provide a device of this character which may be economically constructed of metal channel and bar or strip stock, will be easy to operate between its extended and folded positions, and will reliably support the plurality of garments thereon. It is particularly proposed to provide anti-friction roller means for facilitating the operation of the clothes supporting bar of the hanger.

A further object is to provide manually operable latch means for releasably retaining the clothes supporting bar in its folded position, and which positively retains the bar against accidental or unintentional disengagement under the weight of the clothes supported thereon.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a side elevation of the clothes hanger, according to the illustrated exemplary embodiment of the invention, the same being shown in its extended position.

Fig. 2 is a front elevation in the extended position as shown in Fig. 1.

Fig. 3 is a side elevation showing the clothes hanger in its folded position.

Fig. 4 is a front elevation thereof.

Fig. 5 is a top plan view in the folded position.

Fig. 6 is a horizontal sectional view, taken along the line 6—6 of Fig. 4.

Similar reference characters indicate corresponding parts throughout the several figures of the drawings.

Referring to the drawing, the clothes hanger, according to the illustrated exemplary embodiment of the invention, comprises a vertical supporting member 10 of channel form provided at suitable locations in its base portion with screw holes 11 for attaching the supporting member to a door, wall, or other suitable supporting structure. The upper and lower ends of the supporting member are cut diagonally, as at 12 and 13, so that the left hand flange extends higher than the right hand flange, and the right hand flange ex-

2

tends lower than the left hand flange, the diagonally cut ends permitting this arrangement to be obtained by successively cutting the supports from lengths of channel stock without waste of material. The upper end of the left hand flange is cut square as at 14, and the upper end of the right hand flange and the lower ends of both the left and right hand flanges are cut diagonally, as at 15, so that the hanger does not present sharp corners which might catch on clothes supported upon the hanger.

A retaining and guide bar 16 is secured to the base of the support member 10 by means of rivets 17 and 18, being outwardly offset in parallel spaced relation to the base by means of shoulder bends 19 and 20. The bar 16 is positioned adjacent the right hand flange of the supporting member, and is spaced from the left hand flange to provide a guide slot for the clothes supporting bar, as will presently more fully appear. The upper shoulder bend 19 of the bar 16 is disposed substantially midway between the upper and lower ends of the supporting member and the lower shoulder bend 20 is disposed contiguous to its lower end.

The clothes hanger supporting or hanger bar 21 is formed of a straight length of relatively heavy gauge strip stock, and is provided with a series of equally spaced diagonally disposed key slot openings 22 for engagement therewith of the supporting hooks of a plurality of coat hangers, as indicated by the dot-and-dash lines in Figs. 1 and 2. At the inner end of the bar 21, as shown in its horizontally extended position in Fig. 6, there is provided, within the corner formed by the upper side of the bar and its inner end, a bearing hole 23 rotatably engaged by a transverse pin or stud 24 having a head 25 at one end slidably engaged with the left hand flange of the supporting member 10, the other end of the pin extending beneath the retaining and guide bar 16. Upon the pin 24, there are rotatably engaged apertured disc rollers 26 and 27, the roller 26 being disposed between one side of the bar 21 and the head 25, and the roller 27 being disposed between the other side of the bar 21 and the inner edge of the bar 16. The diameter of the rollers is such that their peripheries extend beyond the corner of the bar 21, so that the bar itself does not contact the base 10. At the same time, the rollers position the pin 24 so that it is in rolling contact with the inner surface of the bar 21.

A strut or suspension bar 28 is connected between the inner side of the upper end of the left hand flange of the supporting member 10 and the

outer side of the bar 21, being pivotally connected to the flange by a rivet stud 29, and pivotally connected to the bar by a rivet stud 30.

A right-angularly shaped swinging latch member 31 is also connected to the left hand flange by the rivet stud 29, being adapted in its vertical position, as shown in Fig. 1, to permit movement of the bar 21 into its vertical folded position, and adapted in its horizontal position, as shown in Fig. 3, to retain the bar 21 in its folded position.

The length of the strut bar 28, and its point of connection with the bar 21, are so proportioned that in the extended position of the bar 21, with the pin 24 engaged with the abutment shoulder 19, the bar 21 is horizontally disposed. The length of the bar 21 between the pivot 30 and its outer end is greater than the length of the bar between the pivot 30 and the pin 24, so that in the horizontally extended position the major weight of the garments supported thereon will be outwardly of the pivot 30, and will therefore tend to maintain the bar in its horizontal position.

The hanger is folded by swinging the outer end of the bar 21 upwardly, causing the pin 24 to move downwardly behind the guide and retaining bar 16 to the point where it engages the lower abutment shoulder 20. In this position the hanger bar and the strut member are disposed in the space between the left hand flange of the supporting member and the edge of the retaining and guide bar 16, thus preventing sidewise displacement or twisting of the bars. In the folded position the latch member 31 is swung into its horizontal retaining position, as shown in Fig. 3.

I have illustrated and described a preferred and satisfactory embodiment of the invention, but it will be understood that changes may be made therein, within the spirit and scope thereof, as defined in the appended claims.

What is claimed is:

1. A clothes hanger comprising a vertical supporting member having a vertically disposed attaching base, vertical slot means carried by said supporting member having a vertical guideway surface parallel to and outwardly spaced from the forward surface of said base and having an abutment stop at a point intermediate the upper and lower ends of said supporting member, a hanger bar in the form of a flat strip wider than said slot means and having side edges and a plurality of longitudinally spaced clothes hanger receiving apertures, a transversely projecting stud at the inner end of said hanger bar engaged with said guideway surface of said slot means for vertical movement longitudinally thereof, a suspension bar pivotally connected at its upper end to said supporting member contiguous to its upper end and pivotally connected at its lower end to said hanger bar intermediate its ends and at a point adjacent the longitudinal edge thereof which is adjacent said base in the vertical folded position of said hanger, said apertures of said hanger bar being disposed substantially adjacent the opposed longitudinal edge thereof, and the width of said suspension bar being substantially less than the width of said hanger bar whereby in the vertical folded position of said hanger bar said suspension bar occupies a vertical position at one side of said hanger bar and at least a substantial portion of each of said apertures is exposed outwardly beyond said suspension bar.

2. A clothes hanger comprising a vertical sup-

porting member in the form of a right angle cross-section strip having a vertically disposed attaching base and a forwardly extending flange at at least one of its vertical edges, vertical slot means carried by said supporting member having a vertical guideway surface parallel to and outwardly spaced from the forward surface of said base and having an abutment stop at a point intermediate the upper and lower ends of said supporting member, a hanger bar in the form of a flat strip wider than said slot means and having side edges and a plurality of longitudinally spaced clothes hanger receiving apertures, a transversely projecting stud at the inner end of said hanger bar engaged with said guideway surface of said slot means for vertical movement longitudinally thereof, a suspension bar pivotally connected at its upper end to the inner side of said flange contiguous to its upper end and pivotally connected at its lower end to a side of said hanger bar intermediate its ends and at a point adjacent the longitudinal edge thereof which is adjacent said base in the vertical folded position of said hanger bar, said apertures of said hanger bar being disposed substantially adjacent the opposed longitudinal edge thereof, and the width of said flange and said suspension bar each being substantially less than the width of said hanger bar whereby in the vertical folded position of said hanger bar said suspension bar occupies a vertical position between said flange and said hanger bar and at least a substantial portion of each of said apertures is exposed outwardly beyond said flange and said suspension bar.

3. A clothes hanger comprising a vertical supporting member having a vertically disposed attaching base, vertical slot means carried by said supporting member having a vertical guideway surface parallel to and outwardly spaced from the forward surface of said base and having an abutment stop at a point intermediate the upper and lower ends of said supporting member, a hanger bar having a plurality of longitudinally spaced clothes hanger receiving apertures, a rotatable transversely projecting stud rotatably mounted at the inner end of said hanger bar engaged with said guideway surface of said slot means for vertical rolling movement longitudinally thereof, a roller rotatably mounted upon said stud having its periphery projected beyond the inner end of said hanger bar and rotatably engaging the forward surface of said base when said hanger bar is angularly disposed with respect to said supporting member whereby as said hanger bar is moved from a vertical to a horizontal position its inner end is guided vertically by said slot means and said roller has rotatable engagement with said base, and a suspension bar pivotally connected at its upper end to said supporting member contiguous to its upper end and pivotally connected at its lower end to said hanger bar intermediate its ends.

4. A clothes hanger comprising a vertical supporting member in the form of a right angle cross-section strip having a vertically disposed attaching base and a forwardly extending flange at at least one of its vertical edges, vertical slot means carried by said supporting member having a vertical guideway surface parallel to and outwardly spaced from the forward surface of said base and having an abutment stop at a point intermediate the upper and lower ends of said supporting member, a hanger bar in the form of a flat strip wider than said slot means and having side edges and a plurality of longitudinally spaced

17 22 27 32 37 42 47 52 57 62 67 72 77 82 87 92 97

clothes hanger receiving apertures, a transversely projecting stud at the inner end of said hanger bar engaged with said guideway surface of said slot means for vertical movement longitudinally thereof, a suspension bar pivotally connected at its upper end to the inner side of said flange contiguous to its upper end and pivotally connected at its lower end to a side of said hanger bar intermediate its ends and at a point adjacent the longitudinal edge thereof which is 10 adjacent said base in the vertical folded position of said hanger bar, said apertures of said hanger bar being disposed substantially adjacent the opposed longitudinal edge thereof, and the width of said flange and said suspension bar each being substantially less than the width of said hanger bar whereby in the vertical folded position of said hanger bar said suspension bar occupies a vertical position between said flange and said hanger bar and at least a substantial portion of each of said apertures is exposed outwardly beyond said flange and said suspension bar, and an angular latch member having a side portion, pivotally mounted on said flange at a point contiguous to its upper end and below the upper 15 20 25

5

end of said hanger bar, in the folded substantially vertical position of the latter, for swinging movement about a horizontal axis, and a retaining portion at right angles to said side portion adapted to be manually swung above the upper end of said flange to unlatching position and adapted to be swung to latching position forwardly of said flange and said hanger bar in said folded position of the latter.
